UNITED STATES PATENT OFFICE

JAMES H. REICHART, OF MUNCIE, INDIANA

ASH RECEIVER

Application filed February 21, 1930. Serial No. 430,194.

This invention relates to a smoker's accessory such as an ash receiver and cigar, match and cigarette extinguisher.

The chief object of the invention is to provide a highly ornamental device capable of functioning as indicated and so constructed that the parts are but few in number, simple in construction and arrangement, simple to operate, and practically fool-proof and indestructible.

The chief feature of the invention consists in the particular construction and cooperation of the several parts permitting permissible discharge of ashes, cigar and cigarette stubs, matches and the like, to an ash receiver and for smothering the same if and when desired.

The full nature of the invention will be understood from the accompanying drawing and the following description and claims.

Fig. 1 is an elevational view of a smoker's vase embodying the invention, parts being broken away to show the same and other parts in central section. Fig. 2 is a top plan view of the invention.

Fig. 3 is an enlarged sectional view of the cooperating portions of the cover stem and match box support.

In the drawing 10 indicates a main body portion of a vase type ash receiver having the foot or base 11 connected thereto by the pedestal or neck 12. A top portion 13 of the vase is extended inwardly and includes a throat 14 and then is extended outwardly as at 15 and terminates in an outwardly flared seat 16, the end of which is protected by a curled or beaded portion 17. Whatever is introduced into the mouth of the vase and is not axially introduced engages the inclined side 15 and discharges toward the throat and through the same into the main body portion 10.

The vase is provided with suitable handles 18 and when the cover construction is removed by lifting the same from the vase, the vase may be readily inverted and the contents of the ash receiving portion discharged through the throat 14. The means for sealing the throat and for forming an ash tray or support for cigars, cigarettes

and the like, and for operating the sealing closure consists of a cover plate, a sealing closure normally constrained toward sealing position, and a cover exposed manually engageable member for operating the closure and supported by the cover.

The cover includes a metal plate having a plurality of segmental downwardly-dished portions 19 adjacent intermediate portions including a ridge 20 that merges with a central portion 21. The outer periphery of the disk is preferably beaded as at 22 and seats upon the inclined portion 16 of the mouth of the vase. Each segmental portion 19 includes a central opening 23 and a plurality of radially arranged slots 24. The arrangement is such that ashes and the like deposited upon each segment portion will either pass through the slots 24 or gravitate toward opening 23 and pass through the same into the vase. The arrangement likewise is such that each segment may be readily cleaned or dusted by the housewife, there being a minimum of interfering corrugations in which ashes, tar or the like can accumulate. The ridged portions 20 constitute the equivalent of a reenforced spider arm for supporting the peripheral rim 22 of the cover. The central portion 21 includes an upwardly extending coaxial embossment 25 apertured as at 26 to slidably receive the rotating and reciprocating rod 27. Rod 27 at its lower end supports a conical closure 28, the same having a projected outline slightly less than substantially that of the throat 14 and the length of the rod 27 is such that the outermost portion of the closure 28 terminates or is normally positioned immediately adjacent the most restricted portion of the throat 14.

In the present invention the cover exposed manually engageable member for actuating the rod 27 consists of a so-called safety match box support. It includes a U-shaped strap and is adapted to lie adjacent the box sides and includes the side portions 30 and the base portion 31. The central or intermediate base portion 31 is provided with a downwardly directed central boss 32 that rides upon or abuts the em-

bossed portion 25 of the cover. A box support consists of an inverted U-shaped member having the top portion 33, the sides 34 and the inwardly directed ends 35, which 5 are extended downwardly as at 36 and thence are projected outwardly as at 37 so that portions 35 and 37 lie parallel to each other and clampingly mount the box support in and upon the U-shaped box protector 30-31. By this construction the angular ends 37 are directed outwardly and clear the base portion 21 of the circular cover and thus unsightly markings on the latter are 10 prevented from forming.

15 The operation of the device is as follows: The cover is positioned in the mouth of the vase. Upon release of the match box support construction secured to the upper end of the actuating rod 27, the cone closure, rod 20 and match box seat themselves in their normal position. Should the rod in this movement be cocked, or other than axial, then the engagement of the cone upon the inclined portion 15 or the portion 14 adjacent thereto will cause the cone to automatically 25 center itself.

In normal usage the ashes may be deposited through the openings and the matches, cigar and cigarette stubs may also 30 be deposited therethrough and they will collect in the throat of the vase and be held there by the cone 28. If the matches or stubs are still smoldering or burning, the fire or blaze may be extinguished by 35 smothering the same. This is accomplished by engaging the match box holder, elevating rod 27, whereupon all of the material deposited in the throat will slide along the sides 15 and adjacent portions 14 of the 40 throat or along the upper surface of the cone closure 28 and pass into the main body of the vase. When this has been accomplished, the match box is released, the cone again seats itself and the flames or fire is 45 smothered. As heretofore indicated in order to remove the debris collected in the vase, all that is necessary is to lift the cover by engaging the openings 23 or by lifting upon the match box. In either event, the 50 cover and cone closure are simultaneously removed from the vase mouth and throat

whereupon the vase may be inverted and the debris removed from the interior thereof.

The invention claimed is:

1. In combination an ash and stub receiving circular throat member having an outwardly flared mouth terminating in a peripheral seat near its open end, a detachable cover nestingly receivable by the mouth seat and including ash and stub receiving openings therein, a conical closure positioned in and substantially sealing the narrowest portion of said throat member, an elongated stem slidably and rotatably supported by the cover, said stem at its lower end and below the cover normally supporting said closure in the throat member, and a match box support exposed above the cover and secured to the upper end of the stem adapted to raise and lower the closure and to rotate the match box. 70

2. In combination an ash and stub receiving circular throat member having an outwardly flared mouth terminating in a peripheral seat near its open end, a detachable cover nestingly receivable by the mouth seat and including ash and stub receiving openings therein, a conical closure positioned in and substantially sealing the narrowest portion of said throat member, an elongated stem slidably and rotatably supported by the cover, said stem at its lower end and below the cover normally supporting said closure in the throat member, and a match box support exposed above the cover and secured to the upper end of the stem adapted to raise and lower the closure and to rotate the match box, 90
